UNITED STATES PATENT OFFICE

2,131,282

AUTOMATIC SWITCH WITH POSITIVE DEFROST AND QUICK FREEZE ADJUSTMENTS

Malcolm E. Henning, Des Moines, Iowa, assignor to Penn Electric Switch Co., Des Moines, Iowa, a corporation of Iowa

Application May 5, 1934, Serial No. 724,092

2 Claims. (Cl. 200—83)

An object of my invention is to provide an automatic switch especially adapted for use in connection with mechanical refrigerators, the switch being comparatively simple, durable and inexpensive to manufacture.

A further object is to provide in a refrigerator switch or the like having defrosting and quick freeze adjustments, a means to positively adjust the switch for either defrosting or quick freezing cycles without such cycles being delayed for sometime after the switch is adjusted to the desired position.

A further object is to provide a defrost and quick freeze adjustable automatic switch of improved characteristics over the switch shown in my copending application Serial No. 699,586, filed November 24, 1933.

Still a further object is to provide a switch or other control device with means for modifying the action of an automatically movable member adjacent either limit of its range of movement and to positively secure the operation desired even though automatic mechanism of the control device tends to prevent securing the desired operation.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of a control switch structure embodying my invention, parts of the cover for the casing being broken away.

Figure 2 is a front elevation of the same.

Figure 3 is a sectional view on the line 3—3 of Figure 2.

Figure 4 is a sectional view on the line 4—4 of Figure 1 and showing the mechanism whereby defrost and quick freeze adjustments can be obtained, the device being adjusted to the normal position.

Figure 5 is a similar view of a portion of Figure 4 showing only the quick freeze mechanism adjusted to the quick freezing position.

Figure 6 is a similar view showing only the parts for defrosting and adjusted to position for obtaining defrosting.

Figure 7 is a sectional view on the line 7—7 of Figure 3; and

Figures 8 and 9 are perspective views of quick freeze and defrosting elements of the control structure.

On the accompanying drawings, I have used

the reference numeral 10 to indicate generally a switch housing. Within the switch housing 10 a control arm 12 is pivoted at 14. Movement of the control arm in one direction is opposed by a spring 16, the arm being moved in such direction by a condition responsive means such as a pressure bellows 18, a capillary tube 20 and a temperature bulb 22.

The spring 16 in conjunction with the bellows 18 operates the control arm 12 through a given range of movement which can be changed in the ordinary manner as by an adjusting screw 24 rotatably mounted and causing movement of a nut 26 when rotated for changing the tension of the spring.

The spring 16 is seated in a cup washer 28 having ears 30 mounted in notches of the control arm 12. For rotating the threaded rod 24 and thus obtaining adjustment, I provide a gear 32 non-rotatably associated with the rod 24 and meshing with a gear 34. The gear 34 has an extension 36 on which a range adjusting knob 38 is mounted. The knob 38 is located adjacent a face plate 40 having suitable indicia thereon for indicating the tension of the spring 16.

The control arm 12 is adapted to swing a switch arm 42 about its pivot 44. This is accomplished in a snap action fashion by a spring 46 interposed between a point element 48 on the control arm 12 and a similar element 50 pivotally associated with the upper end of the switch arm 42. The switch arm 42 is adapted to slide a contact bar 52 for engaging and separating contacts 54 and 56. The arm 42 has a finger 58 engageable with a slot in the contact bar 52 for sliding it when the arm swings.

Defrost and quick freeze mechanism

This mechanism is shown best in Figures 4, 5, 6, 8 and 9. A control knob 60 is provided for it and the face plate 40 has suitable indicating characteristics for the (1) normal or non-defrosting and non-quick freezing, (2) defrosting and (3) quick freeze positions. The knob 60 is connected with a plate-like cam 62 which is constrained to remain in the normal position by a spring 64. The spring 64 has its ends indicated at 66 and 68 crossing each other and spaced on opposite sides of a stop 70 movable with the cam 62 and a stationary stop 72 extending from a stationary plate 74.

Thus the one spring 64 tends to retain the cam 62 in the central or normal position of Figure 4 and to return it from the quick freeze and defrost positions illustrated in Figures 5 and 6 re-

spectively, as the tendency of the spring 64 is to unwind and the ends 66 and 68 to swing toward each other to the position of Figure 4.

- On a pin 76, a swinging arm 78 is pivoted. It has an enlarged end 80 provided with a slot 82 swingable about a pin 84. A pivot pin 86 extends from the arm 78 and an anti-friction roller 88 is journaled thereon. The roller 88 normally contacts with a cam surface 89 of the cam 62.
- 10 A sliding lever 90 is pivoted to the pin 86 and has flanges 92 and 94 bent to the position shown in Figure 8 at its lower end. A slot is provided by rabbeting the flange 94, the bottom of the slot being indicated at 96. This slot is adapted 15 to receive an edge of the stationary plate 74 with the portion of the flange 94 received in a slot 98 thereof to permit sliding movement, yet position the lower end of the lever 90 with respect to the stationary plate 74.
- 15 20 The cam 62 is provided with cam surfaces 100 and 102 in addition to the cam surface 89. The cam surface 89 is formed on a radius from the center of the knob 60 so that a portion of the travel of the cam 62 produces no swinging of 25 the arm 78. When the roller 88 is engaged by the cam surfaces 100 and 102, swinging is accomplished however as shown in Figure 5. The opposite end of the slot forming the cam surfaces and indicated at 91 serves as a reinforcement for the cam plate 62. The flange 92 of the quick freeze lever 90 is adapted to contact with an adjustable stop screw 104 of an extension 12a of the control arm 12 for a purpose to be hereinafter fully set forth.
- 30 35 Spring tension is provided for the arm 78 and the lever 90 and comprises a perforated ear 106 on the lever 90, a spring bolt 108, an adjusting nut 110 and a spring 112.
- The spring connects the adjusting bolt 108 40 with a stationary pin 114.
- 40 45 A defrost lever 116 is pivoted at 118, the pivot pin being stationarily associated with the casing 10 of the switch and the stationary plate 74. The defrost lever 116 has a pin 120 on which an anti-friction roller 122 is journaled. The cam plate 62 has a concentric cam surface 124 for the roller 122 which at one end terminates in a shoulder 126 and adjacent its other end has a normal position depression 128. Both the depression 128 and cam surfaces 130 and 132 are provided for swinging the lever 116 as shown for instance in Figure 6. The lever 116 has a flange 134 to engage a stop screw 136 of the control arm 12.
- 50 55 The lever 116 has a perforated ear 138 with which a spring bolt 140 and adjusting nut 142 are associated. A spring 144 is connected with the stationary pin 114 and with the spring bolt 140.

Practical operation

Assuming certain temperatures arbitrarily, if the refrigerator switch has its range and differential adjusted so that it establishes the circuit at 25° and breaks it at 5°, there is a range of 20° between the on and off cycles.

Assuming that for quick freeze a temperature of minus 5° is desired, then the tension of the spring 112 is added to the effect of the bellows 18 to produce a range between 25° and minus 5° for the quick freeze cycle. The tension of the spring 112 changes the differential by 10°.

When the operator of the switch shifts the knob 60 from the normal position to the quick freeze position, if the refrigerator is not operating, he expects it to commence operating imme-

diate. However, if it has just stopped operating because of the temperature of the refrigerator having been reduced to 5°, the additional 10° range is not sufficient to start it operating as the quick freeze adjustment has the effect of 5 bringing the controlling temperature up to 15° rather than to 25° necessary for starting the refrigerator. Therefore, with the switch shown in my copending application hereinbefore referred to, when the normal range of movement 10 is greater than the additional range procurable for quick freezing, the switch would operate as expected when the temperature of the refrigerator is anywhere between 15 and 25° but would not operate when it is between 5° and 15° at the 15 time of adjusting the knob 60 to the quick freezing position. The same holds true at the other end of the cycle for the defrost mechanism.

Accordingly, I contemplate in my present invention a means to positively cause the refrigerator switch to operate as expected when the knob 60 is adjusted to either quick freeze or defrost positions. This is accomplished when adjusting the knob to quick freeze position by causing the cam surface 102 to positively swing the arm 78 20 downwardly, thus moving the lever 90 downwardly and causing its flange 92 to move the extension 12a of the control arm 12 downwardly from the position of Figure 4 to the position of Figure 5 if it is not already in its down position. 30

Similarly, in adjustment to the defrost position, the cam surface 132 positively lifts the roller 122 and swings the flange 134 of the defrost arm 116 upwardly, causing the extension 12a of the control arm to be raised if it is in its lowered 35 position. Thus the control arm is positively swung to circuit closing position if it is in circuit opening position at the time the control knob 60 is moved to quick freeze position, while it is positively moved from closed position to open 40 circuit position when in the closed position at the time the control knob 60 is moved to the defrost position.

After a quick freeze cycle has been started, the refrigerator will gradually become colder, thus 45 contracting the bellows 18 and permitting the spring 16 to swing the control arm 12 clockwise in Figure 1, thus raising the end 12a thereof from the position of Figure 5 to the position of Figure 4 against the action of the spring 112, whereby it takes longer to open the circuit than normally when the tension of the spring 112 is not superposed on the control arm 12 because of the arm 78 being held in raised position as in Figure 4 by the concentric cam surface 89. 50

Reversely, the spring 144 opposes the spring 16 when the extension 12a of the control arm moves 55 downwardly from the position of Figure 6 to the position of Figure 4.

The anti-friction roller 122 is provided so that 60 friction caused by the spring 144 tending to cause the upper end of the arm 116 to engage the cam surface 124 is not imposed as an additional tension when the roller 88 is swung upwardly from the position of Figure 5 to the position of Figure 4 and reversely the roller 88 is provided to eliminate friction as much as possible when the parts move from the defrost position of Figure 6 to the normal position of Figure 4. 65

The spring 64 for the control knob 60 tends to 70 rotate the cam 62 to its normal position so that any friction with its bearing is not added to the modifying action of the springs 112 and 144.

The depression 128 serves as a means to retain the knob 60 in its normal position in addition to 75

the type of spring illustrated at 64, the spring 144 tending to swing the roller 122 into the depression 128 when the roller and the depression register with each other.

5 Some changes may be made in the construction and arrangement of the parts of my device without departing from the real spirit and purpose of my invention, and it is my intention to cover by 10 my claims, any modified forms of structure or use 15 of mechanical equivalents, which may be reasonably included within their scope.

I claim as my invention:

1. In a control device, a control member movable to two opposite positions, condition responsive means tending to move said control member at times to one of said positions and at other times to the other of said positions, means for modifying the action of said control member as affected by said condition responsive means comprising a pair of elements, manually movable means to position one of said elements in position tending to resist movement of said control member to one of said positions and the other element tending to resist movement of said control member to the other of said positions, said ele- 25

ments each positively moving said control member to the desired position if the control member is, at the time of operation of the element, in the undesired position, one of said elements coacting with said manually movable means to normally tend to retain it in non-operative position. 5

2. In a control device, a control member movable to two opposite positions, condition responsive means tending to move said control member 10 at times to one of said positions and at other times to the other of said positions, means for modifying the action of said control member as affected by said condition responsive means comprising a pair of elements and manually movable 15 means to position one of said elements in position tending to resist movement of said control member to one of said positions and the other element tending to resist movement of said control member to the other of said positions, one of 20 said elements coacting with said manually movable means to normally tend to retain it in non-operative position. 20

MALCOLM E. HENNING. 25
